PORTABLE SEAT AND BACKREST COMBINATION

John M. Hehn, Hammett Acres, Anderson, S.C. 29631

Filed Feb. 13, 1967, Ser. No. 5,890

Term of patent 14 years

(Cl. D15—8)

Fig. 1.

Fig. 2.

FIGURE 1 is a perspective view of a portable seat and backrest combination embodying my new design, and

FIGURE 2 is a perspective view of the article of furniture taken from the rear of FIGURE 1 further illustrating my new design.

I claim:

The ornamental design for a portable seat and backrest combination, substantially as shown.
